UNITED STATES PATENT OFFICE.

GEORGE F. BREUNINGER, OF NEWARK, NEW JERSEY.

DISPLAY RACK.

Application filed February 8, 1922. Serial No. 534,954.

To all whom it may concern:

Be it known that I, GEORGE F. BREUNINGER, a citizen of the United States, and a resident of Newark, in the county of Essex 5 and State of New Jersey, have invented a new and Improved Display Rack, of which the following is a full, clear, and exact description.

This invention relates to improvements in 10 display racks, particularly to a device of this character primarily adapted for displaying newspapers, magazines or similar articles.

An object of the invention is to provide a 15 display rack in which the use of spring arms for holding the articles displayed is practically done away with, and a rack which may be conveniently utilized for supporting a number of newspapers or magazines in 20 such a position that the headlines of the papers or the names of the magazines are all exposed to view.

A further object is to provide a display 25 rack, in which the articles may be readily inserted and with equal facility removed, and a rack which will be simple and practical in construction, strong, durable and efficient in use, neat and attractive in appearance, and comparatively inexpensive to 30 manufacture.

With these and other objects in view, the invention consists in certain novel features of construction and combinations and arrangements of parts, as will be more fully 35 hereinafter described and pointed out in the claims.

In the accompanying drawings:

Figure 1 is a perspective view of my display rack;

Figure 2 is a fragmentary view in front elevation, illustrating the manner in which a number of magazines may be supported in the rack; and

Figure 3 is an edge view of Figure 2.

Referring in detail to the drawings, I have used the reference numerals 1, 1 to 45 designate a pair of parallel uprights connected by suitable cross pieces 2 adjacent each end and cooperating with the cross pieces to form a frame. This frame may either be leaned against a support, suspended 50 from a support, or provided with folding braces, the manner of supporting the frame forming no part of this invention.

Upon the forward face of the uprights 1, I mount a pair of guide rods 3, said rods be-

ing mounted in brackets 4 secured to the uprights. The rods are spaced from the forward faces of the uprights for a purpose which will be more fully hereinafter explained.

The reference numeral 5 designates the intermediate portion of a substantially U-shaped paper holding or rack member, which extends between the upper ends of the uprights 1 and is secured at each end to the uprights by suitable securing devices such as 6. This rack member is of substantially U-shape and its arms 7 lie along the forward faces of the uprights 1, terminating short of the upper ends of the guide rods 3. At a point just above the upper ends of the guide rods, the arms 7 are bent forwardly and downwardly, as indicated at 8, and terminate in a pair of spring arms 9, which extend upwardly and rearwardly and cooperate with the forwardly bent portions 8 to form a seat or rack for magazines, newspapers, or similar articles. It will be noted that in this uppermost rack member, spring arms are utilized to hold the papers. In the remaining rack members which I designate by the reference numeral 10, the use of springs is entirely done away with. Each of the rack members 10 is of wire bent into substantially U-shape, the intermediate portion of said members being uppermost and the arms of the U terminating in hooked extremities 11 which are movable under the guide rods 3 and embrace the uprights 1. Each arm of each member 10 is formed at its intermediate portion with an S bend, the forward loop of said bend providing a seat 14, similar to the seat 8, for a magazine or a newspaper and the rear loop 15 of the S providing a point of attachment for a link 12 suspended from the forward loop of the S bend in the next higher rack member. Links 13 suspended from the seats 8 are pivotally connected to the rear loops of the S bends of the arms of the next lower rack member 10. In similar manner all of the remaining rack members are suspended from each other. Those portions of the arms between the S bends and the hooked extremities 11 form counter-balancing arms 16, which serve to retain the rack members swung inwardly against each other, as seen most clearly in Figure 1. These counter-balancing arms do away with the necessity for the use of springs.

The manner of use of the device is as fol-

lows: When it becomes desirable to insert a magazine or newspaper in one of the racks, the intermediate portion of the rack is grasped and pulled outwardly, the extremities of the arms of said rack sliding upwardly under the guide rods 3. A magazine or newspaper may then be inserted in the rack and when a plurality of such articles are in the rack, as seen in Figures 2 and 10 3, the headlines or titles of each article will be displayed.

Although I have illustrated one of the preferred embodiments of my invention, it will be apparent that various slight changes 15 and alterations might be made in the general form and arrangement of the parts described without departing from the invention, and hence I do not wish to limit myself to the precise details set forth, but shall consider myself at liberty to make such slight changes and alterations as fairly fall within the spirit and scope of the appended claims.

I claim:

1. In a device of the character stated, a 25 supporting frame, a plurality of wire paper holders hingedly connected with each other for movement on said frame and guided in their movement by said frame, each of said holders being substantially U-shape with 30 the intermediate portion of the U uppermost, said holders having leg portions, said legs being provided adjacent their center with substantially S-shaped bends, and links 35 connected to the bent portions of the adjacent holders.

2. In a device of the character stated, a supporting frame, a plurality of wire paper holders hingedly connected with each other for movement on said frame and guided in 40 their movement by said frame, each of said holders being formed in the shape of a U with leg portions, the intermediate portion of the U being disposed uppermost, said legs being provided adjacent their center with 45 substantially S-shaped bends, links connected to the bent portions of the adjacent holders, the bends formed in said legs providing seats for the papers in the holders, said holders pivoting on the links.

50 3. In a device of the character stated, a supporting frame, a plurality of wire paper holders hingedly connected with each other for movement on said frame and guided in their movement by said frame, each of said 55 holders being substantially U-shaped with the intermediate portion uppermost, said

holders having leg portions, said legs being provided adjacent their center with substantially S-shaped bends, links connected to the bent portion of the adjacent holders, 60 the bends formed in said legs providing seats for the paper in the holders, said holders pivoting on the links, and guide rods fixed to the frame, the legs of said holders terminating in hooked extremities movable 65 along the guide rods.

4. In a display rack, a frame, a plurality of paper holders each comprising a single length of wire of substantially U shape, said length of wire having leg portions bent to 70 form paper-receiving seats, all of said holders pivotally connected to each other at opposite points intermediate the length of the legs, the other ends of said leg portions extending beyond the points of connection and 75 acting as counterbalancing means tending to retain the holders against each other, the ends of the legs being slidably connected to the frame.

5. In a display rack, a frame, a plurality 80 of paper holders each comprising a single length of wire of substantially U shape, said length of wire having leg portions, said legs bent to provide paper-receiving seats, all of said holders pivotally connected to each 85 other at opposite points intermediate the length of the legs, and rails fixed to the frame, the outer ends of the legs of said holders extending beyond the points of connection and acting as counterbalancing arms 90 to retain the holders folded against each other, the ends of the legs terminating in hooked structures slidable along the guide rails.

6. As a new article of manufacture, a display rack, comprising a supporting frame, a plurality of wire paper holders suspended from the frame, said holders including integral counter-balancing arms normally retaining the holders folded inwardly against 100 each other.

7. As a new article of manufacture, a display rack comprising a supporting frame, a plurality of wire paper holders swingingly suspended on said frame, said holders including integral counterbalancing arms normally retaining the holders folded inwardly against each other, and means secured to the frame and engageable with the arms to 105 guide the swinging movement of the holders.

GEORGE F. BREUNINGER
